UNITED STATES PATENT OFFICE

115,896

DESIGN FOR A BRASSIÈRE OR SIMILAR ARTICLE

George A. Kaufmann, Essex Fells, N. J.

Application May 20, 1939, Serial No. 35,101

Term of patent 7 years

To all whom it may concern:

Be it known that I, George A. Kaufmann, a citizen of the United States, residing at Essex Fells, county of Essex, State of New Jersey, have invented a new, original, and ornamental Design for a Brassière or Similar Article, of which the following is a specification, reference being had to the accompanying drawing, forming a part thereof.

Fig. 1 is a front view of a brassière showing my new design; Fig. 2 is a back view of the same; and Fig. 3 is a perspective view.

The dominant feature of the design is the laced gore in the center of the back section of a brassière as shown.

I claim:

The ornamental design for a brassière or similar article, as shown and described.

GEORGE A. KAUFMANN.
